UNITED STATES PATENT OFFICE

BEATRICE ALTMAN, OF BROOKLYN, NEW YORK, ASSIGNOR TO L. J. HYAMS AND COMPANY, OF NEW YORK, N. Y.

DESIGN FOR A TEXTILE FABRIC OR THE LIKE

Application filed November 23, 1932. Serial No. 46,120. Term of patent 3½ years.

To all whom it may concern:

Be it known that I, BEATRICE ALTMAN, a citizen of the United States, and a resident of Brooklyn, in the county of Kings, and State of New York, have invented a new, original, and ornamental Design for a Textile Fabric or the like, of which the following is a specification, reference being had to the accompanying drawing, forming part thereof.

The figure is a plan view of a textile fabric or the like, showing my new design.

A complete repeat unit of the design is enclosed between the vertical and horizontal dotted lines.

I claim:

The ornamental design for a textile fabric or the like, as shown and described.

BEATRICE ALTMAN.
